DESIGN.

J. W. BROWN, Jr.
FRAME FOR FRUIT SEEDING MACHINES.

No. 28,607.

Patented May 10, 1898.

UNITED STATES PATENT OFFICE.

JOHN WILSON BROWN, JR., OF PHILADELPHIA, PENNSYLVANIA.

DESIGN FOR A FRAME FOR FRUIT-SEEDING MACHINES.

SPECIFICATION forming part of Design No. 28,607, dated May 10, 1898.

Application filed March 26, 1898. Serial No. 675,328. Term of patent 14 years.

To all whom it may concern:

Be it known that I, JOHN WILSON BROWN, Jr., a citizen of the United States, residing in Philadelphia, Pennsylvania, have invented a 5 certain new and useful Design for the Frame of a Fruit-Seeder, of which the following is a specification.

My design for the frame of a fruit-seeding machine is clearly illustrated in the accompanying drawings, in which—

Figure 1 is a perspective view, and Fig. 2 is a sectional view.

The essential feature of the design is the frame having depending side plates and inclined cross-plates.

A A are the two side plates, having their lower portions a spread apart.

a' a² are two cross-plates arranged at an

angle one in respect to the other. One cross-plate, a', is long and extends diagonally 20 from the back to the front of the frame. The other plate, a², extends from the front to a point a short distance above the other diagonal plate a'.

I claim—

25 The design for the frame of a fruit-seeding machine as herein described and as shown in the accompanying drawings.

In testimony whereof I have signed my name to this specification in the presence of 30 two subscribing witnesses.

JOHN WILSON BROWN, JR.

Witnesses:

WILL. A. BARR,

JOS. H. KLEIN.
